(57) **CLAIM**

The ornamental design for a child carrier with inflatable seat as shown and described.

DESCRIPTION

FIG. 1 is a front view of a child carrier with inflatable seat with an inflatable seat cushion insert located in a main storage compartment underneath a seating surface, wherein the main storage compartment is shown as open with insert inflated;

FIG. 2 is a rear view thereof;

FIG. 3 is a partial side view thereof;

FIG. 4 is a top left side perspective view of the inflatable seat cushion insert in FIG. 1, shown in an inflated state;

FIG. 5 is a top partial side perspective view of the inflatable seat cushion insert in FIG. 4, shown in a deflated state;

FIG. 6 is a front view of the child carrier with inflatable seat of FIG. 1 thereof;

FIG. 7 is a side perspective view of the child carrier with inflatable seat of FIG. 1 in a partially folded state thereof;

FIG. 8 is a side perspective view of the child carrier with inflatable seat of FIG. 1 in a partially folded state thereof;

FIG. 9 is a side perspective view of the child carrier with inflatable seat of FIG. 1 in a partially folded state thereof;

and,

FIG. 10 is a side perspective view of the child carrier with inflatable seat of FIG. 1 in a fully folded state.

The broken lines shown in FIG. 3 represent the boundary box of the environment in which the child carrier with inflatable seat is used and form no part of the claimed design.
